UNITED STATES PATENT OFFICE.

WILLIAM W. KING, OF HUNTSBURG, OHIO.

JUMP-SPARK PLUG FOR EXPLOSION-ENGINES.

No. 923,535.

Specification of Letters Patent. Patented June 1, 1909.

Application filed November 2, 1908. Serial No. 341,698.

To all whom it may concern:

Be it known that I, WILLIAM W. KING, a citizen of the United States, and resident of Huntsburg, county of Geauga, State of Ohio, have invented certain new and useful Improvements in Jump-Spark Plugs for Explosion-Engines, of which I hereby declare the following to be a full, clear, and exact description, such as will enable others skilled in the art to which it appertains to make and use the same.

The objects of the invention are to increase the efficiency, durability and reliability of the "jump spark" firing plug for gasoline or gas engines which are exposed to the weather, and especially for use with engines exposed to sea water, where the saline deposit will gradually coat the exterior surface of the insulation of the plug and form a conducting film, which will be sufficient for the current to travel over from the frame to the central firing pin without jumping the firing gap in the interior of the engine cylinder.

25 The "short circuiting" of the current causes the spark to misfire and the gas in the engine will not explode, and when the gas fails to explode during two or three turns of the engine shaft the engine comes to a 30 dead stop. I remedy this defect by means of the forms of construction and combination and arrangement of parts as herein-after described, shown in the accompanying drawings and specifically pointed out in the 35 claims.

In the accompanying drawings, Figure 1 is a vertical longitudinal section of the device; and Fig. 2 is a horizontal transverse section thereof. Fig. 3 is a bottom view 40 and Fig. 4 is a detail of spark wheel.

In these figures, 1 is the central firing pin, having one end of the circuit wire 2 secured between the nuts 3 and 4.

5 is the insulating block formed of mica, 45 mica paper, porcelain or other insulating material that will not corrode or deteriorate under the influence of weather or heat when subjected to outside exposure. This block insulates the firing pin 1 from the metallic 50 part 6 of the firing plug.

To prevent a film from forming, which will connect the frame or metallic parts of the plug with the firing pin, an annular air space 7 is formed about the firing pin between the 55 pin and the insulating block 5 by enlarging

the central opening in the block. This space increases the distance over which the film of incrusted matter would have to form between the metal base and the firing pin, and also creates an inner surface which can 60 be readily cleaned and kept free from incrustation or water, and is also protected by the long exterior surface. The air space 7 envelops the upper portion and preferably 65 the larger portion of the pin 1.

8 is a cap which is attached to the upper end of the firing pin, and held in place by nut 4, and it is provided with a downwardly turned flange 9 which incloses the upper end of the insulating block 5 and is made enough 70 larger in diameter than the block to leave an air space 10 between itself and the block. This air space should not be less in width than the width of the spark gap so that the current cannot pass to the cap from any 75 film of water or from any incrustation upon the outer surface of the block 5. This cap is preferably formed of some effective insulation that is tough and will stand the weather, and will not be easily broken. It 80 can if necessary, be made of metal.

The object of the cap is to protect the upper part of the outside surface of insulating block 5, but especially the inner surface thereof from spray and dirt, and therefore to 85 keep the inside surface clean, and dry, and preserve its insulating qualities.

The plug 6 screws into the cylinder and forms one terminal of the electric current. The pin 1 has upon its extremity a rotating 90 wheel with inclined vanes 14, which forms the other terminal, with the spark gap 12 arranged between the projecting end of the plug and the vanes. As they rotate in the cavity in the plug, the spark constantly 95 changes its position, and hence the liability of choking the spark by carbon deposit is reduced to the minimum, and the danger of bridging the spark gap is avoided.

The vanes 14 are caused to rotate rapidly 100 after each explosion of gas, and hence the spark gap will be kept open until a complete circular bridge is formed in the inside of the plug, equal in width to the width of the gap.

15 is an annular nut that holds the insulating block 5 in a recess in the plug and bears on the shoulder 16.

17 is a nut which clamps the lower end of the pin 1 in the block 5.

18 is an asbestos or other soft washer 110

which prevents the gas or fumes from the engine from entering the cavity of the insulating block.

I am aware that a closed cavity has been employed in an insulating block to form a vortex of air and gas to expel carbon deposits, but I believe myself to be the first to employ an open but protected air space for the purpose described.

10 Having described the invention what I claim as new and desire to secure by Letters Patent is:—

1. In a sparking device, the combination with a metal plug, of an insulating block secured therein and projecting therefrom, and having an enlarged central opening extending inward from the outer end, a firing pin longitudinally passing through said insulating block and central opening therein, the 15 said opening forming an air space about the body of said pin, a cap secured to the outer extremity of said firing pin and spaced from the adjacent end of the insulator and having an annular flange depending therefrom of 20 larger diameter than said insulating block, and terminating short of the plug whereby 25

an annular air space is formed above and encircling a portion of said block, substantially as described.

2. A sparking device comprising a metal plug forming one terminal of an electric circuit, a firing pin forming the other terminal, an insulating block in said plug projecting therefrom, through which block said firing pin projects, means for securing said insulating block in said plug, and means for securing said firing pin in said insulating block, said block having an enlarged opening therein, extending inward from the outer end about the body of said pin, and a cap secured to the upper end of said pin, and extending vertically downwardly about the exterior of the upper portion of said insulating block and spaced therefrom and terminating short of the plug, substantially as described. 45

In testimony whereof I hereunto set my hand this 31st day of October 1906.

WILLIAM W. KING.
